HEAT EXCHANGE DEVICE

Fritz G. Cornell, Jr., Mountain Lakes, N. J.

Application January 24, 1934, Serial No. 708,032

41 Claims. (Cl. 257—184)

This invention relates to heat exchange devices and more particularly to devices suitable for use in attemperating milk and other liquid products.

5 An object of this invention is a compact, inexpensive and completely enclosed heat exchange device capable of handling a large quantity of liquid in a small space and made up of a plurality of units which are easily movable relative to each other to singly expose each unit, thereby facilitating cleaning of the same.

10 A device embodying the invention comprises a cabinet within which a plurality of heat exchange units are located side by side in parallel arrangement and means are provided for supplying milk or other liquid product to the top of each unit and collecting means are provided below the units. Each unit is mounted for edge-wise or endwise movement independently of the other units so that any unit may be moved away from the remainder to expose it and make it accessible for cleaning.

15 Other objects, novel features and advantages of this invention will be apparent from the following specification and accompanying drawings, wherein:

20 Fig. 1 is a perspective view of the device with the cabinet closed;

25 Fig. 2 is a perspective view of the heat exchange device;

30 Fig. 3 is a plan view with one of the units moved into exposed position;

35 Fig. 4 is a perspective view of the same arrangement as in Fig. 3, and

40 Fig. 5 is a vertical section partially broken away through a unit.

The cabinet is provided with a removable cover 10 and the front wall consists of two hinged doors 11 while one end wall consists of two hinged doors 12. The end wall opposite the doors 12 consists of a casing 13 and the floor or base 14 is provided with a detachable extension 15.

45 Within the cabinet are arranged a plurality of heat exchange units 16, each consisting of a pair of vertical headers 17 and 18 connected by horizontal tubes 19, the headers being provided with baffles 20 to direct liquid serially through the tubes. Each unit is divided into a lower section and into an upper section, the 50 two sections being separate and distinct from each other and each section having its own inlet and outlet. In alinement with the lower tube of each section is provided a stuffing box 22 and in alinement with the top tube of each section 55 there is provided a stuffing box 23. A pipe 24 ex-

tends through the stuffing box 22 and runs substantially the full length of the bottom tube. A packing gland 25 establishes a sliding liquid-tight fit between the pipe 24 and the stuffing box 22. A pipe 26 extends through the nipple 23 and runs substantially the full length of the top tube, and a packing gland 27 establishes a sliding but liquid-tight connection between the pipe and stuffing box. Each pipe 24 is connected to a horizontal header 28 while each pipe 26 is connected to a horizontal header 29. A pipe 30 supplies liquid to the header 28 and a pipe 31 leads liquid away from the header 29.

5 The header or manifold 28 is provided with a series of stuffing boxes 22' in which are arranged the ends of the pipes 24. The end of each pipe 24 is provided with a flange 24' which has a sliding fit in the stuffing box and suitable packing is interposed between this flange and a packing gland 25' which slidably fits the pipe 24 and is screwed into the stuffing box 22'. The header or manifold 29 is provided with a series of stuffing boxes 23' in which are arranged the ends of the pipes 26. The end of each pipe 26 is provided with a flange 26' which has a sliding fit in the stuffing box and suitable packing is interposed between this flange and the packing gland 27' which slidably fits the pipe 26 and is screwed into the stuffing box 23'. In the above-described stuffing box connections, the 25 pipes 24 and 26 inherently have sufficient play to allow slight deviation of the heating units from rectilinear movement without interfering with free telescoping of the units on the pipes.

30 Each heat exchange unit may be moved edge-wise away from the horizontal headers and back to original position without breaking the liquid conducting connections between the horizontal headers and the unit. The units slide on the pipes 24 and 26 and the packing glands maintain liquid-tight relation at all times. Rollers 32 support the units 16 and facilitate endwise movement thereof. The bar 39 pivoted at 39a extends across the right-hand end of the assembly of heat exchange units and is supported at 39b. This bar normally prevents endwise movement of the units and may be swung upwardly about its pivot to release said units for endwise movement.

35 A removable collecting pan 32 is supported beneath the heat exchange units and is provided with a discharge pipe 33 which extends through an aperture in the front wall formed by cooperating recesses in the meeting edges of the doors 11. Each vertical header 17 and 18 is provided 40

below the bottom tube 19 with guide plates 34 which overhang the edges of the pan 32 and insure delivery of all liquid to the pan.

Liquid is supplied to the top tube of each unit by means of a distributor comprising a plurality of perforated pipes 35 resting in grooves in the tops of the headers 17 and 18, a cross pipe 36 connected to each of the pipes 35 and a supply pipe 37 leading to the cross pipe 36. The supply pipe 37 extends to a point outside the cabinet through a slot in the end wall of the casing formed by cooperating recesses in the meeting edges of the doors 12. The liquid supply pipe 30 is provided with a valve 40 having a vertically movable stem 41 on the upper end of which rests a bracket 42 carried by one pipe 35 of the distributor. The weight of the distributor holds the valve stem in depressed position, thereby opening the valve and permitting the flow of liquid through the pipe 30. Removal of the distributor permits the valve stem to rise, thereby closing the valve and preventing flow of liquid through the pipe 30. This arrangement of valve prevents the heat exchange unit 16 from being subjected to hydraulic pressure when the distributor is removed, thus preventing undesirable endwise movement of the heat exchange unit when the cabinet is open for cleaning the units. The bar 39 prevents endwise movement of the units 16 under hydraulic pressure during operation, the bar 39 being removed when it is desired to clean the units.

In operation, the heat exchange units are all arranged in the position shown in Fig. 2, with the pan 32 and bar 39 in place and the distributor arranged with the pipes 35 resting in the sockets in the tops of the vertical headers, the doors 11 and 12 being closed and the cover 10 in place as shown in Fig. 1. A milk supply pipe is connected to the pipe 37 and a milk discharge pipe is connected to the pipe 33. Different cooling media are circulated through the lower and upper sections of the units by way of the pipes 30 and 31 and headers 28 and 29 and the milk flowing down over the pipes is progressively cooled.

After a run has been completed, the extension 15 is attached to the base 14, the cover 10 is removed and the doors 11 and 12 are opened. The distributor is lifted off the tops of the units and removed, thereby closing the valve 40 and the pan 32 is withdrawn. The bar 39 is moved away from the ends of the heat exchange units.

A unit is then pulled out to the position shown in Figs. 3 and 4 by means of the handle 38 in which position it is completely accessible for cleaning. The extension 15 provides a level surface for the rollers 21 to travel over so that movement of the unit back and forth is facilitated. The movement of the unit is accomplished without disconnecting any parts and while the unit is maintained in operative relation to the headers by reason of the fact that the unit has slid out on the pipes 24 and 26. After a unit has been cleaned, it is returned to its original position and is again ready for use. The remaining units are pulled out and cleaned in turn and returned to original position.

After all the units have been cleaned and returned to their original position, the pan and bar are re-assembled therewith, the doors closed, the distributor placed in position and the cover applied, whereupon the device is again ready for use. The enclosing cabinet prevents contamination of the milk and the compact arrangement of the

units gives maximum capacity in minimum space. As the units are movable into and out of cleaning position without disturbing the connections between the headers and the units, there is no leakage of cooling media and the cleaning operation can be accomplished with minimum effort.

The heat exchange device has been specifically described as adapted primarily for cooling milk or other liquids but it is apparent that it may also be used for heating milk or other liquid produced, in which event, the heating fluid will be supplied through the pipe 30 to the headers as above described. It is also understood that various modifications may be made in the structure above described, without in any way departing from the spirit of the invention as defined in the appended claims.

I claim:

1. An attemperating device comprising a plurality of heat exchange units arranged face to face and separable one from the rest by movement in their own planes, and means connected to said units for circulating heat exchange media therethrough in any position of said units.

2. An attemperating device comprising a heat exchange unit, an inlet pipe and an outlet pipe connected to said unit for bodily movement of the latter relative to the former in its own plane.

3. An attemperating device comprising a heat exchange unit, an inlet pipe, an outlet pipe and sliding connections between said unit and pipes for permitting bodily movement of said unit in its own plane relative to said pipes.

4. An attemperating device comprising a heat exchange unit, an inlet pipe, an outlet pipe and telescoping connections between said unit and pipes for permitting bodily movement of said unit in its own plane relative to said pipes.

5. An attemperating device comprising a heat exchange unit, an inlet pipe and an outlet pipe therefor, said inlet and outlet pipes extending substantially through said unit and having liquid-tight sliding connection therewith for permitting bodily movement of the unit in its own plane relative to said pipes.

6. An attemperating device comprising a heat exchange unit, an inlet pipe and an outlet pipe, said heat exchange unit comprising a pair of headers having connecting tubes, said pipes extending into tubes of said unit and having liquid-tight sliding connection with said headers for permitting bodily movement of each unit in its own plane relative to its inlet and outlet pipes.

7. An attemperating device comprising a plurality of heat exchange units each comprising a pair of vertical headers connected by horizontal tubes, an inlet and an outlet pipe for each unit, and telescoping connections between one header of each unit and the inlet and outlet pipes for said unit for permitting individual end-wise movement of the units.

8. An attemperating device comprising a plurality of heat exchange units each comprising a pair of vertical headers connected by horizontal tubes, a pair of superposed horizontal headers, a plurality of pipes extending from the bottom horizontal header into the bottom tubes of said units, and a plurality of pipes extending from the upper horizontal header into the top tubes of said units and sliding liquid-tight connections between said pipes and unit headers.

9. An attemperating device comprising a casing having a base, an extension detachably connected to said base, a plurality of heat exchange units, rollers for said units, each unit consisting

- of a pair of vertical headers connected by tubes, an inlet pipe and an outlet pipe for each unit, each pipe extending into a tube and having a sliding liquid-tight connection with the unit for 5 permitting bodily movement of each unit in its own plane relative to its inlet and outlet pipes, each unit being individually movable endwise from said base onto said extension to render said unit accessible for cleaning.
10. An attemperating device comprising a casing having a base, an extension for said base, a plurality of heat exchange units supported by said base, an inlet pipe and an outlet pipe for each unit, and telescoping connections between each unit and its inlet and outlet pipes for permitting bodily movement of each unit in its own plane relative to its inlet and outlet pipes, each unit being individually movable endwise from said base onto said extension to render said unit 15 accessible for cleaning.
11. An attemperating device comprising a plurality of heat exchange units arranged face to face, supply and discharge headers for said units, and connections between each header and each unit permitting relative bodily movement of each unit in its own plane relative to said headers and to the remaining units.
12. An attemperating device comprising a plurality of heat exchange units, each consisting of 20 a pair of vertical headers connected by horizontal tubes, pipes extending into selected tubes of each unit and sliding liquid-tight connections between said pipes and headers.
13. An attemperating device comprising a casing having a base, an extension therefor, a plurality of heat exchange units supported by said base face to face and separable one from another by endwise movement, and means for circulating heat exchange media through said units, 25 said extension serving to provide a support for a unit when moved out of alinement with the remaining units.
14. An attemperating device comprising a casing having a base, an extension therefor, a plurality of heat exchange units supported by said base face to face, an inlet pipe and an outlet pipe for each unit, and telescoping connections between each unit and the inlet and outlet pipes therefor permitting endwise movement of said 30 unit, said extension serving to provide a support for a unit when moved out of alinement with the remaining units.
15. An attemperating device comprising a casing having a base and having one wall consisting of pivoted doors, an extension for said base, a plurality of heat exchange units within said casing arranged face to face and separable one from another by endwise movement, means for circulating heat exchange media through said units, and rollers supporting said units, said units being movable endwise from said base onto said extension through said doors.
16. An attemperating device comprising a plurality of heat exchange units arranged face to face and separable one from another by endwise movement, means for circulating heat exchange media through said units, said units being provided with recesses at the tops thereof, and a distributor comprising a plurality of pipes overlying 35 said units and being received in said recesses.
17. An attemperating device comprising a casing having a base and one wall consisting of hinged doors, an extension for said base, a plurality of heat exchange units within said casing arranged face to face and separable one from another by endwise movement, means for circulating heat exchange media through said units, and rollers supporting said units, said units being movable endwise from said base onto said extension through said doors.
18. An attemperating device comprising a casing having a base and one wall consisting of two pivoted doors, an extension for said base, a plurality of heat exchange units within said casing arranged face to face and separable one from another by endwise movement, each unit consisting of a pair of vertical headers connected by tubes, an inlet pipe and an outlet pipe for each unit, each pipe extending into a terminal tube and having a sliding liquid-tight connection with the unit for permitting bodily movement of each unit in its own plane relative to its inlet and outlet pipes, rollers supporting said units, said units being movable from said base onto said extension through said doors, said headers being provided with recesses at the tops thereof, and a distributor comprising a plurality of pipes seated in said recesses.
19. An attemperating device comprising a casing having a base and one wall consisting of two pivoted doors, an extension for said base, a plurality of heat exchange units within said casing arranged face to face and separable one from another by endwise movement, each unit consisting of a pair of vertical headers connected by tubes, an inlet pipe and an outlet pipe for each unit, each pipe extending into a terminal tube and having a sliding liquid-tight connection with the unit for permitting bodily movement of each unit in its own plane relative to its inlet and outlet pipes, rollers supporting said units, said units being movable from said base onto said extension through said doors, said headers being provided with recesses at the tops thereof, a distributor comprising a plurality of pipes seated in said recesses, a second wall of said casing consisting of two pivoted doors, and a collecting pan removably mounted on said base beneath said units, said pan being removable through said last-named doors.
20. An attemperating device comprising a plurality of heat exchange units arranged face to face, an inlet pipe and an outlet pipe for each unit, telescoping connections between each unit and its inlet and outlet pipes permitting endwise movement of the unit, a first header to which said inlet pipes are connected, a second header to which said outlet pipes are connected, a supply pipe leading to said first header, a discharge pipe leading from said second header, a self-closing valve in said supply pipe, and a distributor removably supported above said heat exchange units, said distributor having means engaging said valve to open the same.
21. An attemperating device comprising a plurality of heat exchange units arranged face to face, an inlet pipe and an outlet pipe for each unit, telescoping connections between each unit and its inlet and outlet pipes permitting endwise movement of the unit, a first header to which said inlet pipes are connected, a second header to which said outlet pipes are connected, a supply pipe leading to said first header, a discharge pipe leading from said second header, a self-closing valve in said supply pipe, a distributor removably supported above said heat exchange units, said distributor having means engaging said valve.

- to open the same, and a movable locking bar for retaining said heat exchange units in face to face relation.

22. An attemperating device comprising a plurality of heat exchange units arranged face to face, an inlet and an outlet pipe for each unit, telescoping connections between each unit and its inlet and outlet pipes permitting movement of the unit in its own plane, and a movable locking bar for retaining said units in face to face relation.

23. An attemperating device comprising a plurality of heat exchange units arranged face to face, an inlet and an outlet pipe for each unit, telescoping connections between each unit and its inlet and outlet pipes permitting movement of the unit in its own plane, and means for preventing movement of said units under hydraulic pressure developed therein during operation of the device.

24. An attemperating device comprising a plurality of heat exchange units arranged face to face and separable one from another by movement in its own plane, a pipe for supplying heat exchange medium to said units, a self-closing valve in said supply pipe and a distributor assembly supported above said heat exchange units, said distributor having means engaging said valve to open the same.

25. An attemperating device comprising a plurality of heat exchange units arranged face to face and separable one from another by movement in its own plane, a pipe for supplying heat exchange medium to said units, a self-closing valve in said supply pipe and a distributor assembly supported above said heat exchange units, said distributor having means engaging said valve to open the same, and means for preventing movement of said units under hydraulic pressure developed therein during operation of the device.

26. An attemperating device comprising a plurality of heat exchange units arranged face to face and separable one from another by movement in its own plane, means connected to said units for circulating heat exchange media therethrough in any position of the units, and a distributor supported above said units for supplying thereto liquid to be attemperated.

27. An attemperating device comprising a plurality of heat exchange units arranged face to face, inlet and outlet pipes connected to each unit for bodily movement of each unit in its own plane relative to its said pipes and to the remaining units, and a distributor overlying said units.

28. An attemperating device comprising a plurality of heat exchange units arranged face to face, inlet and outlet pipes for said units, sliding connections between each unit and its pipes for permitting bodily movement of said unit in its own plane relative to said pipes and to the remaining units and a distributor overlying said units.

29. An attemperating device comprising a plurality of heat exchange units arranged face to face, inlet and outlet pipes for said units, telescoping connections between each unit and its pipes for permitting bodily movement of said unit in its own plane relative to said pipes and to the remaining units and a distributor overlying said units.

30. An attemperating device comprising a plurality of heat exchange units arranged face to face, inlet and outlet pipes for said units, the supply and discharge pipes for each unit extending substantially therethrough and having liquid tight sliding connection therewith for permitting bodily movement of each unit in its own plane

relative to its pipes and the remaining units, and a distributor overlying said units.

31. An attemperating device comprising a casing, an openable wall, a plurality of heat exchange units supported within said casing face to face and being individually movable in their own planes through said openable wall, and means for circulating heat exchange medium through said units in any position of said units.

32. An attemperating device comprising a casing, an openable wall, a plurality of heat exchange units supported within said casing face to face and being individually movable in their own planes through said openable wall, and inlet and outlet pipes for each unit, each pipe extending into and having a sliding liquid-tight connection with its unit.

33. An attemperating device comprising a casing having a base and having an openable wall, an extension for said base, a plurality of heat exchange units supported within said casing on said base face to face and being individually movable endwise from said base on to said extension through said openable wall, and means for circulating heat exchange medium through said units.

34. An attemperating device comprising a casing having a base and having one wall openable, an extension for said base, a plurality of heat exchange units supported within said casing on said base face to face and being individually movable endwise from said base on to said extension through said openable wall, and means for circulating heat exchange media through said units, and a distributor overlying said units.

35. An attemperating device comprising a casing having a base and an openable wall, an extension for said base, a plurality of heat exchange units supported within said casing on said base face to face and being individually movable 40 endwise from said base on to said extension through said openable wall, and inlet and outlet pipes for each unit, each pipe extending into and having a sliding liquid-tight connection with its unit.

36. An attemperating device comprising a casing having an openable wall, a plurality of heat exchange units supported within said casing on said base face to face and being individually movable in their own planes through said openable 50 wall, and inlet and outlet pipes for each unit, each pipe extending into and having a sliding liquid-tight connection with its unit, and a distributor overlying said units.

37. An attemperating device comprising a casing having a base and an openable wall, an extension for said base, a plurality of heat exchange units supported within said casing on said base face to face and being individually movable endwise from said base on to said extension through 60 said openable wall, inlet and outlet pipes for each unit having liquid-tight telescoping connections, a second openable wall for said casing, a collecting pan removably mounted on said base beneath said units and being removable through said last-named wall, and a distributor overlying said units.

38. An attemperating device comprising a plurality of heat exchange units supported face to face and being individually movable in their own planes, inlet and outlet pipes for said units, a first header to which said inlet pipes are connected, a second header to which said outlet pipes are connected, a supply pipe leading to said first header, a discharge pipe leading from said second header, and a collector pan removably mounted on said base beneath said units.

- ond header, a self-closing valve in said supply pipe, and a distributor removably supported above said heat exchange units, said distributor having means engaging said valve to open the same.
- 5 39. An attemperating device comprising a casing having a base and an openable wall, an extension for said base, a plurality of heat exchange units supported within said casing on said base face to face and being individually movable end-10 wise from said base on to said extension through said openable wall, inlet and outlet pipes for said units, a first header to which said inlet pipes are connected, a second header to which said outlet pipes are connected, a supply pipe leading to said 15 first header, a discharge pipe leading from said second header, a self-closing valve in said supply pipe, and a distributor removably supported above said heat exchange units, said distributor having means engaging said valve to open the same.
- 20 40. An attemperating device comprising a casing having a base and an openable wall, an extension for said base, a plurality of heat exchange units supported within said casing on said base face to face and being individually movable end-25 wise from said base on to said extension through

said openable wall, inlet and outlet pipes for said units, a first header to which said inlet pipes are connected, a second header to which said outlet pipes are connected, a supply pipe leading to said first header, a discharge pipe leading from said second header, a self-closing valve in said supply pipe, a distributor removably supported above said heat exchange units, said distributor having means engaging said valve to open the same, and releasable locking means for retaining 10 said heat exchange units in face to face relation.

41. An attemperating device comprising a plurality of heat exchange units arranged face to face, a pair of headers, inlet and outlet pipes for said units, and telescoping connections between each unit and its pipes for permitting bodily movement of each unit in its own plane relative to said pipes and to the remaining units, said pipes being connected at one end to said headers with sufficient play to permit slight deviation of said heating units from rectilinear movement without interfering with free telescoping of said units on said pipes.

FRITZ G. CORNELL, JR. 25
